MAXENCE JOSEPH SIDOINE ALEXIS ISNARD, OF GRENOBLE, FRANCE, ASSIGNOR TO PAUL DREVET AND LOUIS AUGUSTIN NOVE-JOSSERAND, OF LYON, FRANCE, AND NOEL DUMOND, OF TASSIN LA DEMI-LUNE, NEAR LYON, FRANCE.

STARTING DEVICE FOR MOTORS.

No. 882,946.

Specification of Letters Patent. Patented March 24, 1908.

Application filed March 20, 1906. Serial No. 306,987.

To all whom it may concern:

Be it known that I, MAXENCE JOSEPH SIDOINE ALEXIS ISNARD, a citizen of the Republic of France, residing in Grenoble, in said Republic, have invented certain new and useful Improvements in Starting Devices for Motors, of which the following is a specification.

The present invention has for its object 10 certain improvements in the apparatus for starting the motors of motor vehicles and other motors, in which, for effecting the starting, a liquefied or highly compressed gas (such as liquid carbonic acid, for example) is utilized and in which as soon as the starting has been effected an appropriate 15 clutch mechanism permits of utilizing the power of the motor itself for the purpose of bringing the gas back to its initial pressure 20 and volume.

In order to simplify apparatus of the above kind, the improvements in accordance with the present invention consist mainly in the direct action, without the intermediary of a 25 liquid, of the compressed or liquefied gas (especially carbonic acid) upon a piston. The rectilinear movement thereby produced is transformed into a circular movement by a 30 rack propelled by the piston and meshing with a spur pinion the shaft of which meshes with the shaft of the motor.

The improvements forming the object of the invention also relate to an apparatus by means of which it is possible to return the 35 rack of the apparatus to its initial position after the motor has been started, so that the apparatus may be ready for again starting the motor.

In order that the invention may be readily 40 and clearly understood the apparatus in question is represented by way of example applied to a motor vehicle, where it replaces the starting handle.

Figure 1 is a front elevation of the starting 45 device; Fig. 2 is a plan view.

The used carbonic gas is not recuperated by the running of the motor. The low price of liquid carbonic acid and the small quantity required for producing a starting 50 pulse, do not justify in many cases any complication of the mechanism.

As soon as the rack moves forward, a

sleeve with clutch teeth slides on the shaft of the small gear wheel and communicates its rotation to the shaft of the gas or spirit 55 motor. In its forward movement the rack which has received the action of the carbonic acid, has overcome the resistance of the motor and has at the same time compressed a spiral spring which has become compressed 60 towards the other extremity of the cylinder.

When the rack has reached the end of its travel the carbonic gas is automatically exhausted and it is then under the influence of the spiral spring, which extends, so that 65 the rack is returned to its initial position. At the same time the clutch sleeve slides on the shaft of the pinion, releasing the shaft of the explosion motor, which then rotates freely. The apparatus is ready for again 70 starting the motor when this latter, after having been stopped, is to be restarted.

In order to obtain the above results, the apparatus comprises broadly a cylinder *a* bored throughout its entire length and arranged horizontally and transversely at the front part of the vehicle in case the device is to be used in connection with a motor vehicle. This cylinder or tube *a* is provided at its intermediate portion with a double bearing 80 which the shaft *c* of a pinion *c* passes, the pinion being arranged within the cylinder, as shown. Extending longitudinally within the cylinder is a rack *b* meshing with the pinion *c* and provided at each end with a piston *b*. On the splined shaft *c* a toothed sleeve *d* is slidable, said sleeve being provided with a serrated face and forming one member of a clutch, the other member of which is similarly formed and arranged upon the end 90 of the motor shaft *m*. By sliding the clutch member *d* along the shaft *c* said member may be made to engage the other member of the clutch and thereby clutch in the motor shaft. 95

Within the cylinder *a* is arranged a helical spring *e*, said spring being interposed between one piston *b* and a plug *g* screwed into one end of the cylinder. Said spring tends to force the rack *b* and its pistons toward and 100 against a plug *f* which is screwed into the cylinder at the opposite end, and is provided with an opening or passage *f*' which serves to conduct the charge of carbonic acid required

for the starting impulse. A slot *h* is formed longitudinally in the cylinder at the side containing the spring *e*. Said slot is of a length equal to the travel of the rack and serves as a guide for a rod *i* connected with and extending laterally from said rack. By means of said rod *i* the angular displacement of the rack relatively to the cylinder is prevented. The rod *i* has an extension *i'* extending longitudinally of the cylinder exteriorly thereof, this extension being adjustably connected to the exhaust cock *k* of the cylinder. In this manner the exhaust of the carbonic acid gas at the precise moment when the first explosion takes place in the motor can be produced.

The discharge aperture may be readily regulated, for each motor, exactly to the fraction of the necessary stroke of the rack. The total stroke of the rack is limited on the one hand by the total compression of the spiral spring and on the other hand by the position of the orifices *o*, formed in the cylindrical wall of the cylinder for the discharge of the carbonic acid gas, when these orifices are uncovered by the piston upon which the gas acts. Further, as soon as it is started, the rod *i* acts throughout its entire stroke upon a leaf spring *j*, so to engage the sleeve *d* with the crank shaft of the motor. When the rack returns to its normal position, the rod *i* leaves the spring *j* which then maintains the sleeve *d* out of engagement.

To provide for backward travel of the motor, which might be due to a premature explosion, in consequence of the advance of the ignition, or to the running back of the motor upon an incline, at the beginning of the rack a part free from teeth is left where the pinion *c* is able to rotate freely.

The front extremity of the shaft of the pinion *c* may be adapted for the reception of a starting handle of the ordinary kind.

The provision of the pinion *c* with pointed teeth and the addition of a heavy mass at a certain part of this pinion assure an invariable position of repose for this pinion, so that engagement with the rack is always certain.

In certain cases in which the motor moment necessitates that the pinion *c* should be of larger diameter, which would entail an excessive length for the rack *b* and consequently for the cylinder *a*, instead of using one pinion *c* the sleeve may be acted upon by an intermediate gear wheel multiplying or dividing the action of the pinion in contact with the rack.

Having thus described my invention, I claim as new and desire to secure by Letters Patent:

1. The combination, with the cylinder, of a shaft mounted transversely thereof, a pinion on said shaft, a rack meshing with said pinion and movable longitudinally in said cylinder, a clutch member slidable on said shaft, and an operative connection between said rack and said clutch member.

2. In a starting device, the combination of a cylinder, a piston-carrying element movable therein, a shaft to which said element transmits its movement, a clutch member slidable on said shaft, and a connection between said element and said member whereby the latter is slid along said shaft in opposite directions according to the direction of movement of said element.

3. In a starting device for motors, the combination of a cylinder having a longitudinal slot, a rack in said cylinder, pistons carried by said rack at the ends thereof, a shaft carrying a pinion meshing with said rack, a clutch member slidable on said shaft, and an operative connection between said rack and said clutch member, said connection embodying a device extending through the slot in said cylinder.

4. In a starting device for motors, the combination of a cylinder, an element movable longitudinally therein, a clutch comprising a shiftable member driven by said element, means for moving said clutch into and out of operative position, and means carried by said element for operating said means and opening the cylinder to the escape of gas.

5. In a starting device for motors, the combination, with the cylinder and the element movable longitudinally therein, of a shiftable clutch member driven by said element, means connecting said element with said clutch member and comprising a device carried by said element for shifting said clutch member into and out of operative position, and means carried by said last-named means for opening the cylinder to the escape of gas.

6. In a starting device for motors, the combination, with the cylinder and the element movable longitudinally therein, of a clutch member driven by said element, means for shifting said clutch member into and out of operative position, a rod carried by said element to operate said shifting means, a cock to open the cylinder to the escape of gas, and an extension on said rod to operate said cock.

7. In a starting device for motors, the combination, with the cylinder and the element movable longitudinally therein, of a clutch member driven by said element, means normally holding said clutch member in inoperative position, and means carried by said element to shift said first-named means and thereby move said clutch member into operative position.

8. In a starting device for motors, the combination, with the cylinder and the element movable longitudinally therein, of a clutch member driven by said element and

shiftable in axial direction, a spring connected with said clutch member which normally holds the same in inoperative position, and a rod carried by said element and projecting through the cylinder-wall into engagement with said spring.

In testimony whereof I have signed this

specification in the presence of two subscribing witnesses.
